UNITED STATES PATENT OFFICE.

HARRY COUSINS AND JOHN WILLIAM BOTSFORD, OF CARDIFF, ENGLAND.

PAPER PUNCH OR PERFORATOR.

1,049,676.

Specification of Letters Patent.

Patented Jan. 7, 1913.

Application filed October 23, 1911. Serial No. 656,150.

To all whom it may concern:

Be it known that we, HARRY COUSINS and JOHN WILLIAM BOTSFORD, subjects of the King of England, both residing at Cardiff, 5 Wales, have invented certain new and useful Improvements in Paper Punches or Perforators, of which the following is a specification.

This invention relates to improvements 10 in paper punches or perforators.

The paper punch or perforator for perforating papers obliquely across the corner is, according to this invention, adapted to punch two or more holes and has an adjustable right-angle gage.

The invention further comprises a paper punch or perforator for perforating papers obliquely across the corner and having punches for perforating either round or rectangular perforations at will.

The invention also comprises certain details which will be hereinafter more fully described.

In the accompanying drawings—Figure 1 25 is a side elevation in part section of a punch adapted to make either rectangular or circular perforations at will; Fig. 2 is an end elevation, and Fig. 3 a plan view of the device.

Like letters indicate like parts throughout.

Referring to the drawings, which show a punch adapted to make either rectangular or circular perforations at will, on a base A⁴, of wood or any other material is fixed 35 a metal casting B³ which carries, by means of brackets B⁴ a pair of punches D³ adapted to punch circular perforations, and a pair of punches D⁴ adapted to punch rectangular perforations. The lower part of the punch 40 support B⁴ also forms a stripper by means of which the perforated sheet is drawn off the punches as they rise after operating. On the top of the casting B³ is pivotally mounted a handle C². Fig. 1 shows a circular spring D⁵ surrounding the punches D³.

Fig. 2 shows the method of mounting the spring-member to govern the rectangular punches D⁴. The punches are connected together at their upper end by means of a cross-piece D⁶, and a vertical stud D⁷ is situated centrally between the punches and is screwed between the two brackets B⁴ B⁴. The stud passes through a hole in the cross-piece D⁶, and a spring D⁸ surrounds the stud

and bears at its lower end against the bracket B⁴ and at its upper end against the cross-piece D⁶. A plate D⁹, held in position by means of screws D¹⁰ incloses the spring and bolt, and in Fig. 2 the plate is not shown for the sake of clearness. When the pivoted handle C² is depressed on either side a projection C³ situated close to the axis of the handle bears against either the circular punches D³ or rectangular punches D⁴. If the handle is further depressed, one pair of punches will be depressed to the limit of their travel, and will perforate the paper placed beneath them.

The base A⁴ is fitted with a metal plate 70 perforated at points just below the punches, the punches co-operating with these perforations or dies. A gage L³ is employed for the purpose of insuring that the papers or the like shall be punched in the same position for each successive operation of the 75 punch. The gage or V-guide is rectangular, and has small holes L⁴ in its two wings. In the casing B³ are fitted a pair of screw studs L⁵ which engage with the holes L⁴. It is thus possible readily to adjust the rectangular gage L³ to any desired position. 80 By unscrewing the studs L⁵ the gage L³ can be withdrawn, and replaced in the punch in the reverse direction, thus affording a gage for use with both the circular and rectangular punches.

Papers and the like perforated by this punch can be fastened, tied or attached together through the holes punched obliquely across the corner by being either tied together loosely, or tightly by tapes, string, laces, clips or other means. Papers thus secured possess many advantages over other methods, in that papers can be easily turned over and at the same time, securely fastened 90 without the danger of tearing the paper. If the rectangular gage L were removed and replaced by a straight one it would be possible to punch holes at the sides or tops of sheets of paper in the known way.

If desired, the punch could be constructed so as to perforate either round or rectangular perforations at will, by making the punches interchangeable or by the employment of two distinct systems of linkage 105 which could either be operated by the same or by different handles. The base could be made of any suitable material such as alu-

minium, or if desired, wood. The plate J is preferably made of steel in order that it shall not get damaged by the action of the punches. Further, the arm B if desired, 5 could be cast solid with the base A.

What we claim as our invention and desire to secure by Letters Patent is:—

1. In a perforator for sheet material the combination of a base, dies in the base, a 10 plurality of gangs of punches to coöperate with the dies, a support for the punches a lever operatively disposed in relation to the punches to operate one gang at a time, a movable guide adapted to position the sheet 15 to be perforated in relation to whichever gang of punches is to be used so that the holes punched are on a line lying obliquely across the corner of an inserted sheet, and means to hold the guide in correct position.

2. In a perforator for sheet material the combination of a base, dies in the base, a plurality of gangs of punches to coöperate with the dies a support for the punches a lever operatively disposed in relation to the 25 punches to operate one gang at a time a movable V-guide adapted to position the sheet to be perforated in relation to whichever gang of punches is to be operated, and means comprising pins borne by the punch 30 support coöoperating with a corresponding number of series of holes in the guide to hold and position the said guide correctly upon the base so that the holes punched are on a line lying obliquely across the corner of 35 the sheet placed in the guide.

3. In a perforator for sheet material the combination of a base, dies in the base, two 40 gangs of punches to coöperate with the dies, a support for the punches which also constitutes a stripper, a lever pivoted on the punch support to swing in one plane only, adapted when swung to one side of the pivot to operate one gang and when swung to the other side of the pivot to operate the other 45 gang of punches, and a reversible adjustable V-guide to position the sheet to be perforated in relation to either gang of punches,

and means to hold and position the guide correctly upon the base.

4. In a perforator for sheet material the 50 combination of a base, dies in the base, two gangs of punches to coöperate with the dies, a support for the punches which also constitutes a stripper, a lever pivoted on the punch support to swing in one plane only, 55 adapted when swung to one side of the pivot to operate one gang and when swung to the other side of the pivot to operate the other gang of punches, a reversible adjustable V-guide, and means comprising threaded pins 60 adjustably screwed through the punch support and coöperating each with a series of corresponding holes in each wing of the V-guide to hold and position the said guide correctly upon the base so that the holes 65 punched are on a line lying obliquely across the corner of the sheet positioned by the guide.

5. In a perforator for sheet material the 70 combination of a base, gangs of rectangular punches, gangs of circular punches, dies co-operating with the punches, a slotted support in which the punches are slidingly mounted a lever operatively disposed in relation to the punches to operate one gang 75 at a time, means to return the punches to inoperative position, means for securing the rectangular punches together in a gang comprising a cross piece D⁶, a stud D⁷ secured in the punch support passing through a hole 80 in the cross piece and guiding a return spring D⁸ and a retaining plate D⁹ holding the punches in the slots of said slotted support, and an adjustable reversible guide to 85 position the sheet to be perforated.

In testimony whereof we have signed our names to this specification in the presence of two subscribing witnesses.

HARRY COUSINS.

JOHN WILLIAM BOTSFORD.
